UNITED STATES PATENT OFFICE.

PHILIP ARGALL, OF DENVER, COLORADO.

CLASSIFIER.

1,044,845.

Specification of Letters Patent. Patented Nov. 19, 1912.

Application filed July 17, 1911. Serial No. 639,051.

To all whom it may concern:

Be it known that I, PHILIP ARGALL, citizen of the United States, residing at Denver, in the county of Denver and State of Colorado, have invented certain new and useful Improvements in Classifiers, of which the following is a specification, reference being had therein to the accompanying drawing.

This invention relates to an improvement 10 in apparatus for treating precious metal bearing ores and more particularly to apparatus for classifying or separating slime from sand. In an apparatus of this character the fineness of the slime is largely dependent upon the character of the weir employed, as if the weir is short the water and slime from the settling tank will flow thereover with such velocity that there will be carried thereover some coarse slime and even 15 some fine sand, while when a long weir is utilized, the water flows thereover in a thin film and at a slow speed so that only the finest slime is carried over the weir.

The object of the present invention is the 25 provision of an apparatus of this character which is so constructed as to afford a very long weir over which the suspended slimes are flowed from the settling portion, so that with the apparatus slimes of great fineness 30 may be obtained.

A further object of the present invention is the provision in an apparatus of this character of a weir for the settling portion of the classifier, the length of which may be 35 adjusted thus rendering it possible by varying the length of such weir, to obtain with the apparatus, slimes of any desired degree of fineness.

Other objects of the invention will be apparent from the detailed description herein-after when read in connection with the accompanying drawings forming a part hereof, wherein a convenient embodiment of the invention is illustrated and wherein like 45 characters of reference refer to similar parts in the several views.

In the drawings:—Figure 1 is a top plan view of the improved classifier; Fig. 2 is a longitudinal section thereof; Fig. 3 is a cross 50 section on line 3—3 of Fig. 2; Fig. 4 is an enlarged cross sectional view showing the

settling tank, the overflow launder, and the weir; Fig. 5 is a cross section through the wall of the settling tank showing the dam in elevation, and Fig. 6 is a cross section 55 through the wall of the settling tank, taken at the overlapping portions of two sections of the dam.

Referring now more particularly to the drawings, A designates a suitable base or 60 support upon which the various parts of the classifier or separator are supported. Mounted upon the support or base A adjacent one end thereof is a settling tank B which is in the present instance, circular 65 in cross section. Mounted upon the support A is a suitable frame work C which serves to support the major portion of the U-shaped trough D, which is arranged at an angle of about fifteen degrees to the supporting base 70 A and the lower end of which projects into the wall of the circular settling tank B. The portions of the side walls of the trough D adjacent the settling tank B are extended above the level of the top of said settling 75 tank so that when the settling tank is full of liquid, such liquid will also extend into the lower portion of the trough. Mounted within the trough D and extending the full length thereof are a pair of oppositely disposed solid or ribbon spiral conveyers E E, 80 the lower ends of which project into the settling tank B. The conveyers E E are carried by suitable shafts, the lower ends of which are journaled in step bearings e e 85 conveniently carried by the wall of the settling tank B and the upper ends of which are journaled in suitable bearings secured to the supporting frame C beyond the upper ends of the trough D. The conveyers E E 90 are intergeared to rotate in opposite directions through the medium of intermeshing gears E' E' which are keyed to the respective shafts thereof. Any suitable means may be employed for driving the conveyers 95 and in the form of the invention illustrated in the accompanying drawings, I have shown the shaft of one of such conveyers provided with a large bevel gear E² which is adapted to be engaged by a suitable 100 pinion E³ mounted on a power shaft which may be operated in any desired manner.

In practice the conveyers are adapted to be rotated very slowly, conveniently from 3 to 8 revolutions per minute. The shafts of the conveyers E E are conveniently arranged parallel to the bottom wall of the trough D and such shafts are so positioned that the conveyers will be spaced a slight distance from the bottom of such conveyer to enable a portion of the sand carried upwardly by the conveyers from the settling tank B to form a bed or bottom in the trough conforming to the conveyers and over which the main body of the material may feed in its course upward and onward.

On the bottom of the trough D and extending the full length thereof are secured a pair of angle irons d d which are located just outside of the edges of the conveyers E E and which are of relatively short height to constitute with the side walls of the trough, overflow channels d'.

In addition to the bearings provided for the ends of the conveyer shafts, means are also conveniently provided for supporting such shafts intermediate the ends thereof.

In the form of the invention illustrated in the drawings, the means provided for this purpose comprises a pair of metal beams F F which are secured to the upper edges of the trough D adjacent the lower end thereof and which extends transversely of said trough. Positioned between the beams F F and supported thereby so as to depend therefrom, are a pair of U-shaped hangers F' F' which embrace suitable boxings f f for the intermediate portions of the conveyer shaft. The U-shaped hangers may be supported in any way from the beams F F so that they may be adjusted vertically to take up any wear on the conveyer shafts for the boxes f f. In the form shown in the drawings, the arms of the U-shaped hangers pass through plates f' which are rigidly secured to the undersides of the beams F F and through cap plates f² f² which fit over the tops of the beams F F and are held in position by suitable securing nuts which are threaded upon the upper ends of the U-shaped hangers F' F' and engage the tops of said cap plates.

Obviously by adjusting the nuts on the upper ends of the U-shaped hangers, such hangers may be adjusted longitudinally. To normally prevent rotary movement of the boxes f f in the hangers F' F' bolts F² F² are employed which are positioned between the beams F F and the lower ends of which engage suitable recesses formed in the upper portions of the boxes f f. The bolts F² F² pass through suitable openings in the cap plates f² f² and also through nuts which are seated in squared openings formed in the underside of said cap plates and normally rest upon the tops of the beams F F. It will thus be seen that the

bolts F² F² may be adjusted with the hangers F' F' to take up any wear on the conveyer shafts or the boxes f f. The boxes f f are conveniently provided with sockets in the undersides thereof which are similar to those in the upper sides of said boxes which are engaged by the lower ends of the bolts F² F², so that when the upper portions of said boxes become worn, they may be reversed in the hangers F' F'.

Extending transversely across the lower end of the trough D is a feed launder or trough G which is adapted to receive the pulp from the stamp batteries, such launder or trough being provided in its forward wall with a series of openings g arranged in the lower portion of said wall, from which the pulp is discharged into the trough of the classifier. The feed launder G may be positioned over any part of the trough which constitutes a continuation of the settling tank B. In practice, however, I prefer to position such feed launder at some distance from the connection of the trough with the settling tank so that the heavy sands will not enter the settling tank but will be pushed upward by the screw conveyers as fast as they fall thereon, thus leaving the tank for the free settling of the finest sands.

Positioned across the lower end of the trough D is an angularly disposed deflector plate D' which is supported in any suitable manner from the upper portion of the side walls of the trough.

Secured upon the exterior of the settling tank B and extending around the upper edge thereof is an overflow trough or launder H. The trough or launder H is conveniently U-shaped in cross section, and the ends of the trough terminate adjacent the connection of the trough D with the settling tank B. In the present embodiment of the invention the overflow trough or launder H is supported upon an angle iron H' which is secured upon the exterior of the settling tank B and extends therefrom, such overflow trough or launder being slightly spaced from the overflow tank by suitable spacing blocks and rigidly secured thereto by fastening bolts passing through said spacing blocks and the walls of the overflow launder and settling tank. The space between the settling tank B and the inner wall of the overflow launder H is conveniently filled with concrete, such concrete filling, however, terminating short of the upper edges of the walls of the overflow launder and settling tank, thus forming a channel h² between the wall of the overflow launder and the settling tank. Seated within the channel thus formed and extending for the full length thereof is a weir I, the upper edge of which is truly level and projects above the upper edges of the settling tank B and launder H. The weir I is conveniently formed of a wooden

strip which is of less thickness than the width of the channel in which it is seated and such weir is rigidly secured in said channel by means of suitable packing *i* which is interposed between the lower portion of the weir and the wall of the settling chamber B. There is thus formed above the packing *i* a channel between the adjacent faces of the weir and the wall of the settling chamber, and in the channel thus formed is removably secured a dam K. The dam K is of such a width that when secured in position in its channel the upper edge thereof will project above the upper edge of the portion of the weir I adjacent thereto, so that it will be seen that such portion of the weir I as the dam K overlies, will not be brought into use during the operation of the device. In order that the operative length of the weir may be adjusted to any desired extent, the dam K is preferably formed of a plurality of overlapping sections K'. The sections K' of the dam may be overlapped to any desired extent to adjust the length of such dam as may be desired, and as many of such sections may be utilized, as may be found desirable. To facilitate adjustment of the sections K' of the dam in the channel at the top of the wall of the settling chamber, such sections are conveniently provided with set screws projecting from the upper portions thereof, which constitute handles permitting the ready adjustment of the sections in the channels. The sections K' of the dam fit in the channel rather snugly and the channel is of such a depth as to prevent tilting of such sections. If desired, means may be employed for positively locking the sections in the channel but no such means need necessarily be employed.

From the construction thus described it will be seen that if the dam K is not utilized, the entire length of the weir will be effective, thus providing a very long weir, which is highly desirable, and in fact, is necessary when a slime of a very fine mesh is to be obtained, as when a very long weir is employed, the water from the settling tank will flow thereover in a thin film at a very slow rate, thus carrying only the finest slime. At times, however, when it is not desired to obtain slime of the greatest degree of fineness, it is desirable to operate the device with a shorter weir and in this event, the dam K is utilized to cut off a portion of the weir. Obviously by adjusting the dam to the desired extent, any desired amount of the weir can be cut out of operation and the operative portion of the weir may be made as short as is found desirable. This feature of the invention is an exceedingly important one as by varying the speed at which the conveyers are driven, and varying the operative length of the weir,

the machine can be so adjusted to give slime of any desired degree of fineness. It will also be noted that by reason of the substantially circular form of weir employed, applicant is enabled to obtain a weir of great length in a comparatively small area. The overflow launder is provided with a suitable discharge opening H² through which the slime is discharged.

In the operation of the improved classifier, the pulp composed of the crushed ore and cyanid solution from the stamp batteries or other crushing device, together with a suitable amount of water, is supplied through the feed launder G to the lower portion of the trough D, which is in communication with the settling tank B and into which the water from the settling tank extends. This portion of the trough D really constitutes a part of the settling chamber of the apparatus, the remainder of the trough, in which no water from the settling tank extends, constituting an "unwatering portion". As the material is fed into the lower portion of the trough D, and from thence into the settling tank B, it will be agitated by reason of the constant actuation of the spiral conveyers E E and the greater portion of the slime will be separated from the sand and flow over the edge of the weir I and into the overflow trough H. As the sand settles to the bottom of the tank B and the settling portion of the trough D, a sand bed is gradually formed and progressively built upward upon the inclined bottom of the trough, the upper surface of which is complementary to the contour of the conveyers. As this bed or bottom is formed the main or movable body of sand with its confined slime, is forced upwardly by the spiral conveyers, into the unwatering portion of the trough. During this operation the conveyers are constantly changing and displacing the sand particles which causes the slime to be squeezed out of the sands and to be returned to the settling tank by the channels formed between the flanges *d* on the bottom of the trough D and the walls of such trough. This squeezing out or extracting out of slime from the moving body of sand is accomplished by the agitation of the body under the influence of the spiral conveyers, and owing to the pressure upon the body created by the force which moves the same forward and upwardly, resisted by the inertia of the body itself. The slime freed sand is discharged from the upper end of the trough D, from whence it is conveyed in any suitable manner into the leaching tanks, where it is treated in the well known manner, or the sands may be returned to a tube mill or other fine grinding machine for further reduction. In the all-sliming process a classifier of the character herein described and a tube mill

arranged in circuit will give a continuous slime overflow of the desired fineness, while the sands would be continuously returned to the mill or mills for further grinding.

5. While a convenient embodiment of the invention is illustrated in the accompanying drawings, it will be understood that many changes may be made to the form and construction therein shown without departing from the spirit and scope of the invention as defined in the appended claims.

I claim:

1. In a classifier of the character described, the combination with a settling chamber having a weir at its edge, of an unwatering trough leading from the settling chamber, of a size in cross-section at its lower end less than the width of the chamber, a conveyer entering the settling chamber and passing through the trough, a feed at the lower end of the trough, and a deflector interposed between the feed and the settling chamber, substantially as described.

2. In a classifier of the character described, the combination with a settling chamber having an overflow weir at its edge, of an unwatering trough entering the side of the settling chamber, of a size in cross-section at its lower end less than the width of the chamber, a plurality of oppositely operating conveyers extending toward the bottom of the settling chamber and through the trough, a feed adjacent the lower end of the trough, and a deflector positioned at a point between the trough and the weir, for the purposes stated.

3. In a classifier of the character described, the combination with a substantially circular settling chamber having a trough surrounding the same on the outer side, an unwatering conductor trough leading from the separating chamber of a size in cross-section at its lower end less than the width of the chamber, a conveyer extending from the separating chamber into the unwatering trough, means for operating the conveyer, and a feed for the settling chamber located adjacent the end of the unwatering trough at a point beyond the settling chamber.

4. In a classifier of the character described, the combination with an enlarged settling chamber, of an unwatering trough leading therefrom of a size in cross-section at its lower end less than the width of the chamber, a weir at the edge of the settling chamber, a conveyer located within the trough, and projecting into the settling chamber, and a feed for the settling chamber located above the lower end of the unwatering trough at a point in advance of the settling chamber whereby the feed will be deposited in the liquid contained in the lower end of the trough, for the purposes specified.

5. In a classifier of the character described, the combination with a settling chamber, of an unwatering trough leading therefrom and of a size in cross-section at its lower end less than the width of the chamber, an overflow weir for the chamber, a conveyer in the unwatering trough and a feed for the chamber.

6. In a classifier of the character described, the combination with a settling chamber having a weir at its edge extending substantially the length thereof, and a removable dam member adjustably supported at the edge of the settling chamber extending above the plane of the weir and of a length less than the length of the weir.

7. In a classifier of the character described, the combination with a settling chamber having an extended weir at its upper edge, of a removable sectional dam member supported at the edge of the settling chamber and projecting above the plane of the weir and of a length less than the length of the weir, substantially as described.

8. In a classifier of the character described, a settling tank, an overflow trough secured upon the exterior of said settling tank and extending for a substantial distance therearound, said overflow trough being spaced from said settling tank to provide a channel therebetween, a weir seated in the channel between the overflow trough and the settling tank, the upper edge of said weir projecting above the upper edge of the settling tank, and a dam removably supported in said channel so as to overlie a portion of said weir, said dam being of a height to project above the upper edge of the weir.

9. In a classifier of the character described, a settling tank, an overflow trough secured upon the exterior of said settling tank and extending for a substantial distance therearound, said overflow trough being spaced from said settling tank to provide a channel therebetween, a weir seated in the channel between the overflow trough and the settling tank, the upper edge of said weir projecting above the upper edge of the settling tank, and a longitudinally extensible dam seated in said channel and overlying a portion of said weir, said dam being of a height to project above the upper edge of the weir.

10. In a classifier of the character described, an annular settling tank, an overflow trough secured to the exterior of said settling tank and extending for a substantial distance therearound, said overflow trough being spaced from the wall of the settling tank, a filling in the space between the overflow trough and the wall of the settling tank, said filling terminating short of the top of the settling tank to pro-

vide a channel between the upper portion of the overflow trough and the wall of the settling tank, a weir supported in the channel thus formed and co-extensive therewith, said weir being of a thickness to partially fill the channel, and a dam removably supported in said channel alongside of said weir and adapted to overlie a portion thereof.

In testimony whereof I affix my signature in presence of two witnesses.
